[57] ABSTRACT

A multi-purpose refuse collection vehicle. The vehicle includes a body provided with an internal refuse compactor and a refuse inlet for receiving refuse to be collected and compacted. A delivery device is associated with the inlet for delivering refuse received in the inlet to the interior of the body for compaction. A removable chute is superimposed over the inlet and has an enlarged, upper refuse receiving opening and a lower refuse discharging opening, the latter overlying the inlet. A lift structure is mounted on the vehicle for gripping a refuse container to move the same to a discharge point above the chute and redeposit the container on the underlying terrain. Alternately, the lift structure can be employed to remove the chute from the vehicle so that the vehicle can be selectively conditioned for collection of refuse from large containers or from small containers dumped or deposited directly into the inlet.

AUTOMATED REFUSE COLLECTION VEHICLE

BACKGROUND OF THE INVENTION

This invention relates to a refuse collection vehicle and, more particularly, to a refuse collection vehicle that may be selectively conditioned for collecting refuse from large containers such as those typically attendant commercial or industrial operations or for collecting refuse in residential areas where the refuse is separately wrapped or contained in relatively small containers.

Relevant prior art includes U.S. Pat. Nos. 3,802,585 to Churchman; 3,809,267 to Knight; and 3,815,765 to Moser et al.

Mechanized refuse handling and disposal is on a substantial upsurge by reason of the high cost of labor. To eliminate the labor cost, there has been a tendency in the industry to go towards increased mechanization. The above identified prior art patents are typical of vehicles developed in the trend toward increased mechanization.

Typically, the vehicles require a crew of at least two, including a driver and a helper. To increase the labor savings, it is highly desirable that the need for a helper in addition to the driver be minimized or eliminated entirely.

Additionally, refuse collection vehicles generally fall into two distinct categories. One category of vehicle is that designed for the collection of refuse in, for example, low density residential districts, such as single family dwelling districts. In such areas, the refuse will normally be in relatively small containers such as conventional garbage cans, or possibly self-contained as in disposable plastic bags or the like.

The other type of vehicle is that intended for the collection of refuse from districts of higher intensity uses such as commercial, industrial or multiple family residential districts wherein the refuse is frequently dumped into large containers which, in turn, are carted away.

Consequently, in a given area where both light and heavy uses are present, it is necessary that two distinct types of refuse collecting vehicles be employed. Of course, in such a case, initial expenditure for the equipment is substantially greater than if one type of vehicle could be employed for collection of refuse for both types of uses.

SUMMARY OF THE INVENTION

It is the principal object of the invention to provide a new and improved refuse collection vehicle. More specifically, it is an object of the invention to provide such a vehicle that minimizes the need for attendant manual labor and which is readily conditioned for use in collecting refuse from large containers typically associated with commercial or industrial uses as well as relatively small containers typically associated with residential use.

An exemplary embodiment of the invention achieves the foregoing object in a construction including a wheeled vehicle having a body which includes interior refuse compacting means. The vehicle mounts a refuse inlet for receiving to be collected and compacted. A driving device is associated with the inlet for delivering refuse received therein to the interior of the body for compaction while a removable chute is placed over the inlet and includes an enlarged upper refuse receiving

opening. The vehicle is provided with a moving means which may be operated to grip a large refuse container and move the same to a discharge point above the chute upper opening to deposit refuse in the container into the chute and thereafter return the container to its resting point. Alternately, the moving means may be employed to remove the chute from the vehicle so that the vehicle may be used in the collection of refuse in small containers simply by having the containers dumped directly into the inlet.

According to a preferred embodiment of the invention, a door is movably mounted on the body in proximity to the chute upper opening when the chute is in place on the vehicle. Means are provided for moving the door between positions opening and closing the refuse receiving opening in the chute.

The invention also contemplates provision of an operator cab on the vehicle with the inlet located between the cab and the body. The moving means comprises a boom structure mounted on the vehicle and extending forwardly of the cab.

A preferred form of boom structure includes a pair of lift arms pivoted to the vehicle about a generally horizontal axis and a lift fork pivoted to the lift arms about a second generally horizontal axis spaced from the first. A pair of jacks are employed for selectively pivoting the lift arms about the first axis and the lift fork about the second axis.

In one form of the invention, the lift fork includes horizontally orientable tines that are adapted to embrace the sides of a large refuse receiving container. The tines are provided with hook formations for receipt in respective collars on the sides of the container.

One embodiment of the invention also contemplates that the jacks be connected to the lift arm or to the lift fork, as the case may be, with toggle linkages.

Other objects and advantages will become apparent from the following specification taken in connection with the accompanying drawings.

DESCRIPTION OF THE DRAWINGS

FIG. 1 is a side elevation of a refuse collecting vehicle made according to the invention;

FIG. 2 is a fragmentary side elevation of the vehicle illustrating the position of various components when a large refuse receiving container is being dumped;

FIG. 3 is a fragmentary side elevation illustrating how a chute employed on the vehicle may be removed;

FIG. 4 is a fragmentary side elevation of a modified embodiment of the vehicle; and

FIG. 5 is a fragmentary side elevation of the modified embodiment illustrating a large refuse container being dumped into a chute on the vehicle.

DESCRIPTION OF THE PREFERRED EMBODIMENTS

An exemplary embodiment of a refuse collection vehicle made according to the invention is illustrated in FIG. 1 and is seen to include a vehicle frame, generally designated 10, journalling wheels 12 by which means the vehicle may travel over the underlying terrain 14. The vehicle frame mounts a body, generally designated 16, having interior compacting means (not shown). Preferably, the interior compacting means take on the form disclosed in the previously identified Moser et al patent, the details of which are incorporated by reference.

The body 16 has a rear door 18 which may be operated by a hydraulic cylinder 20 to allow the body to be emptied as desired. Again, the structure is like that disclosed by Moser et al.

Forwardly of the body 16 is an upwardly open inlet, generally designated 22, having a floor 24. The floor 24 extends rearwardly to a ramp 26 below the body 16 and contained within the frame 10 is a hydraulic ram 28 which may be operative to reciprocate a plunger 29 across the inlet 22. Upon such reciprocation, refuse within the inlet 22 will be moved into the body 16 for compaction therein. For more specific details of the arrangement thus far described, the reader is again directed to the previously identified Moser et al. patent.

The vehicle includes an operator cab, generally designated 30, which will be disposed to one side of the center line of the vehicle. The cab 30 will, of course, house suitable controls for the vehicle propulsion system as well as for the various jacks and rams heretofore or hereinafter described. As can be seen, the cab 30 is located such that the inlet 22 is between the body 16 and the cab 30. By reason of this construction, a nesting area above the inlet 22 is provided such that a removable chute, generally designated 32, can be located in superposed relation with respect to the inlet 22. The chute 32 includes an enlarged, upper refuse receiving opening 34 (FIG. 2) and a lower refuse discharging opening (not numbered) immediately above the opening of the inlet 22 so that refuse delivered into the chute 32 through the opening 34 will pass to the inlet 22 under the influence of gravity. Additionally, road shock and vibration, when the vehicle is moving, will cause the refuse in the chute 32 to settle within the inlet 22.

A door 36 is pivoted as at 38 to the body 16 and is configured to completely close the refuse receiving opening 34 of the chute 32. To move the door 36 to an open position, such as that shown in FIG. 2, a hydraulic cylinder 40 is pivotally mounted as at 42 to the body 16 and has its piston rod connected by a pivot pin 44 to the junction of links 46 and 48. The links 46 and 48 are pivotally connected as at 50 and 52 to the door 36 and the body 16 respectively. Consequently, upon retraction of the rod of the cylinder 40, the door 36 may be moved from the closed position shown in FIG. 1 to the open position shown in FIG. 2 for receipt of refuse.

Returning to FIG. 1, the vehicle mounts a moving means, generally designated 54, for moving a large refuse container 56 from an at rest position on the underlying terrain 14 to a discharge position above the opening 34 as illustrated in FIG. 2. The moving means 54 includes a pair of L-shaped lift arms 57 (only one of which is shown), each having one end pivotally connected by a pin 58 to a bearing block 60 secured to the vehicle frame 10. The opposite end of each of the arms 57 mounts, by means of a pivot pin 62, an L-shaped lift fork structure 64. For strengthening purposes, a cross member 66 may extend between the lift arms 57.

A hydraulic cylinder 68 has one end pivotally connected as at 70 to the vehicle frame, while its rod 71 is connected by a pivot pin 72 to the lift arms 57. A second cylinder 74 is pivotally connected by a pin 76 to the lift arms 57 or the cross member 66, if desired, while its rod is connected by a pivot pin 78 to the fork lift structure 64.

As a result of the foregoing structure, it will be appreciated that the disposition of the lift arms 57 with re-

spect to the vehicle may be altered by appropriate energization of the cylinder 68, while the disposition of the fork lift 64 with respect to the lift arms 56 may be similarly varied through energization of the cylinder 74.

Typically, a large refuse container such as the container 56 will include transverse strengthening members 80 spaced below the bottom wall thereof. Thus, the driver of the vehicle may move the same forwardly and through appropriate energization of the cylinders 68 and 74 cause the horizontally extending arms 82 of the fork lift 64 to enter the space between the cross members 80 and the bottom of the container 56. Further energization of the cylinder 68 to raise the lift arms 57 will result in the container 56 being moved to the position illustrated in FIG. 2 whereupon refuse therein will be deposited in the chute 34 provided, of course, that the door 36 has been previously opened. The procedure may then be reversed to redeposit the container 56 on the underlying terrain.

FIG. 3 illustrates the means by which the moving means 54 may be operated to remove the chute 32 so that refuse in small containers may be deposited directly into the inlet 22 as when collection is being made through a single family residential area. Specifically, with the rod of the cylinder 74 fully withdrawn, the fork lift 64 will be in the solid line position illustrated in FIG. 3. The ends of the same are provided with heavy duty eyes 88 for receipt of chains 90. The chains 90, in turn, may be connected to outwardly projecting lugs 92 on the side of the chute 32. With the arms 57 fully elevated and the fork lift 64 in the solid line position, the rod of the cylinder 74 may then be extended to move the fork lift to the dotted line position. This will result in the chute 32 being moved to the dotted line position illustrated in FIG. 3. Thereafter, the lift arms 57 may be lowered until the chute 32 engages the underlying terrain as shown in dotted lines. At this point in time, the chains may be removed and the vehicle backed away from the chute, fully conditioned for residential refuse pickup. The chute 32 may be replaced by following substantially the reverse of the above procedure.

A somewhat modified embodiment of the invention is illustrated in FIGS. 4 and 5. The same is in all essential respects identical to that previously described with the exception of the structure of the moving means 54. In the case of the embodiment illustrated in FIGS. 4 and 5, two lift arms 100 (only one of which is shown) are employed. Rather than being L-shaped, the two ends thereof diverge from each other at an angle other than 90°. One end is pivotally connected as at 102 to a bearing block 104 secured to the frame, while the other end, by means of pivots 106, mount two, horizontally orientable, tines 108 (only one of which is shown). A hydraulic cylinder 110 has its rod connected to a pivot 112 joining links 114 and 116. The link 116 is pivotally connected as at 118 to the vehicle frame while the link 114 is pivotally connected as at 120 to the lift arms 100. As a result, a toggle type linkage is formed for elevating the lift arms 100.

A somewhat similar toggle type linkage is employed for changing the attitude of the tines 108 with respect to the lift arms 100. Specifically, an arcuate link 122 is pivotally connected by a pin 124 to the lift arms 100 and by a pin 126 to the rod 128 of a hydraulic cylinder 130. The latter is, in turn, connected by a pivot pin 132 to the lift arms 100.

A link 134 receives the pivot pin 126 and is also pivotally connected as at 136 to the tines 108. Thus, through appropriate energization of the cylinder 130, the toggle linkage thus defined is operative to change the attitude of the tines 108.

The tines 108 are especially adapted to be received in circular collars 140 which may be secured to opposite sides of a refuse container 142. Preferably, the outermost end of each tine 108 is provided with a hook like formation 146 so that, upon initial elevation, firm 10 and positive retention of the refuse container 142 on the fork lift structure defined by the tines 108 is provided.

For removal of the chute 32 with the embodiment illustrated in FIGS. 4 and 5, a roller 150 may be journaled on pivot pin 112. Chains may be secured from any suitable point on the tines 108 to the lugs 92. When the lift arms 100 are fully elevated, as shown in FIG. 5, the roller 150 will abut the forwardmost side of the chute 32 so that when the latter is elevated through rotation of the tines 108 in a clockwise fashion about the pivot pin 106, the chute 32 will be guided upwardly in such a fashion as to not come into damaging contact with the cab 30. Once the chute 32 has been suitably elevated by operation of the tines 108, the lift arms 100 may be lowered to bring the chute 32 into engagement with the underlying terrain. Of course, replacement of the chute 32 may be had by reversing the above procedure.

From the foregoing, it will be appreciated that a refuse collection vehicle made according to the invention accomplishes the previously stated objects of minimizing the need for attendant labor while providing an apparatus that is suitable for collection of refuse both from large containers and from small containers. When the vehicle is being employed in connection with the pickup of refuse from large containers, such as the containers 56 or 142, a single operator may be employed to both drive the vehicle and operate the collection mechanism. Thus, the need for a helper is eliminated. It will also be appreciated that by simple removal of the chute 32 through the use of the lift structure, the vehicle can be conditioned for pickup of small self-contained refuse articles or refuse contained in relatively small containers since the same may be simply deposited within the inlet 22 in the same fashion contemplated in the previously identified Moser et al. patent.

We claim:

1. A refuse collection vehicle comprising:
a wheeled vehicle;
a body on said vehicle, said body including interior refuse compacting means;
a refuse inlet on said vehicle for receiving refuse to the collected and compacted;
means associated with said inlet for delivering refuse

received therein to the interior of said body for compaction therein;
a removable chute on said vehicle and superposed over said inlet, said chute having an enlarged, upper refuse receiving opening and a lower refuse discharging, said refuse discharging opening overlying said inlet whereby refuse deposited in said chute will be directed to said inlet; and
moving means mounted on said vehicle for (a) gripping a refuse container resting on underlying terrain adjacent said vehicle, (b) moving the refuse container to a discharge point above said chute upper refuse receiving opening so that refuse in the container will be deposited in said chute, (c) returning the container to the underlying terrain, and alternatively (d) removing said chute from and replacing said chute on said vehicle whereby said vehicle may be selectively conditioned for collection of refuse in large containers through said chute and from small containers directly emptied into said inlet when said chute is removed.

2. The refuse collection vehicle of claim 1 further including a door movably mounted on said body in proximity to said upper refuse receiving opening when said chute is on said vehicle; and means for moving said door between positions opening and closing said upper refuse receiving opening.

3. The refuse collection vehicle of claim 1 wherein said vehicle includes an operator cab and said inlet is located between said cab and said body; and said moving means comprises a boom structure mounted on said vehicle and extending forwardly of said cab.

4. The refuse collection vehicle of claim 3 wherein said boom structure comprises a pair of lift arms pivoted to said vehicle about a first generally horizontal axis, a lift fork pivoted to said lift arms about a second generally horizontal axis spaced from said first axis; a first jack for selectively pivoting said lift arms about said first axis, and a second jack for selectively pivoting said lift fork about said second axis.

5. The refuse collection vehicle of claim 4 wherein said lift fork has horizontally orientable tines adapted to be received in a space below the bottom of a refuse container.

6. The refuse collection vehicle of claim 4 wherein said lift fork has horizontally orientable tines adapted to flank the sides of a refuse container, the ends of said tines being provided with hook formations for receipt of respective collars on the sides of a refuse container.

7. The refuse collection vehicle of claim 4 wherein said first jack is connected to said lift arms through a toggle linkage.

8. The refuse collection vehicle of claim 4 wherein said second jack is connected to said lift fork through a toggle linkage.
